UNITED STATES PATENT OFFICE.

SIMON GROSSMAN, OF PITTSBURGH, PENNSYLVANIA.

SUITCASE.

1,397,374.

Specification of Letters Patent. Patented Nov. 15, 1921.

Application filed April 29, 1920. Serial No. 377,596.

To all whom it may concern:

Be it known that I, SIMON GROSSMAN, a citizen of the United States, residing at Pittsburgh, in the county of Allegheny and 5 State of Pennsylvania, have invented certain new and useful Improvements in Suitcases, of which the following is a specification.

My invention relates to improvements in 10 suitcases, or as they may be termed traveling cases, and the improvements are particularly directed to the construction of a binder for the surrounding edges of the cover and body of the case and a reinforcing 15 and supporting frame structure for these parts.

One object of my invention is to provide 20 a metal binder for the surrounding edges of the cover and the body portion, which binder on these portions of the case is clamped upon the fibrous or other material from which the cover and body portions 25 are made up to reinforce these edges, and in so shaping the binder that when the cover is closed the binder of the two portions interfits to give a snug closing joint and a double reinforcement in that portion which would otherwise be the weakest section of the case.

Another object is to provide metal frame 30 and corner pieces which are associated with and riveted or otherwise secured to the metal binder and which reinforce and strengthen the case on all corners and on those edges 35 which receive the most severe shocks and strains in use.

Yet another object resides in applying the binder in a manner that it strengthens 40 and reinforces the portions of the cover and body of the case on which the hinges, the lock, and other fastenings for the case are secured, the arrangement being such that these fastenings are riveted or otherwise secured directly in conjunction with the reinforcing frame of which the binder forms 45 a part.

A still further object is to construct and 50 arrange the binder and other supporting and reinforcing portions in such a manner that a maximum of reinforcing strength will be secured by the use of relatively thin sheet metal which can be worked with facility and can be applied to and secured upon the material of the body and cover.

With these and other objects in view 55 which will be apparent from the drawings,

specification and claims, this invention consists of certain novel features of construction and combinations of parts which will now be set forth.

In the drawings:

Figure 1 is a view in perspective showing a case constructed in accordance with my invention.

Fig. 2 is a sectional view taken transversely through the case.

Fig. 3 is a detail sectional view through the edges and binder portions of the cover and body.

Fig. 4 is a view similar to Fig. 3.

Fig. 5 is a fragmentary perspective view of a corner of the body of the case showing the association and connection of the binder, corner, and frame portions.

Fig. 6 is a detail sectional view through the cover and body portion adjacent the corner.

Fig. 7 is a fragmentary perspective to better illustrate the manner in which the cover and body binders interfit.

Fig. 8 is a detail sectional view of a modified form of binder for cover and body portion of the case.

The body of the cover of the case is indicated at B and the cover C is made to close over the opening thereto. These portions are made of fiber board or other suitable material, cut and bent to provide rim portions 1 and 2 on the body and cover.

A binder 3, of thin sheet metal, is provided for the edge of the rim portion 2 of the cover, and this binder extends on the inner side substantially over the entire width of the rim to strengthen and reinforce the same, the outer edge of the binder 95 being extended sufficiently to give a smooth and neat finish over the edge of the rim 2. It is preferable that binder 3 be turned in on both its edges as no edge is then presented and at the same time the binder is 100 stiffened and reinforced.

In applying the binder it is preferably cut in lengths corresponding to the various sides of rim portion 2 and is fitted over and clamped upon the edges thereof. Corner 105 pieces 4 are then placed over the corners of the cover to embrace the meeting ends of the sides of rim 2 and rivets 5 are inserted through these corner pieces and through the inside thickness of binder 3 110 and are clenched upon the same. Rivets 6 are passed through the corner pieces and the

main portion of the cover and are clenched or headed to unite these parts.

The binder 7 for the rim 1 of body B is made with its inner edge sufficiently wide 5 to give a considerable overlap on the inner face of rim 1 and is bent and shaped to provide an offset at 8 to receive the binder 3 when the cover is closed against the body, a lip 9 being provided at the inner side of 10 the offset to fit within the cover binder. The binder 7 is cut into lengths corresponding to the sides of rim portion 1 and is fitted over and clamped upon the edge thereof, angularly shaped sheet metal frame portions 15 10 are then placed over the abutting edges of the sides of the rim portion 1 with one end of each frame member overlapping binder 8. Corner pieces 11 are fitted on the corners of the body portion B and rivets 20 12 are penetrated through the corner pieces, the frame pieces, and the material of rim 1, these rivets being clenched to securely connect the various portions. Rivets 13 secure the frame pieces 10 in place, certain 25 of these rivets being passed through the binder 8 and clenched or headed thereagainst.

By this assembly of the binder 7, frame pieces 10, and corner pieces 11, the body is 30 given a firm supporting frame around the edge of the opening and on the edges and corners of the rim 1, where the most severe strains and shocks will be received in use. Also, the corner pieces 4 with binder 3 give 35 a similar supporting and reinforcing frame on the cover, and as the binder 3 interfits with binder 7, the cover, when closed, gives support to the body, and the reverse, the corner pieces 4 and 11 and frame members 40 10 forming substantially continuous reinforcing for the corners.

As has been stated, it is preferable that binder 7 be applied in separate lengths on each of the sides of the rim 1 of body B, and 45 to provide for the offset 8 portions of the lip 9 are bent down as shown at 14 in Fig. 5, these bent down portions acting to still further strengthen and stiffen the binder.

The hinges 15 are secured on the rim portions 1 and 2 of the body and cover by means 50 of rivets 16 and 17, and these rivets pass through and are clenched or headed over against the long inner edge of the binders 7 and 3. The catches 18 and the two portions of the lock 19 are secured in like manner by the rivets 20 and 21 which pass through the inner edge of the two binders. Further, it is preferable that the handle 22 55 of the case be so placed that at least one of 60 the fastening rivets 23 at each end be received through the inner edge of binder 7.

An important feature of my invention is the construction of the binder strips for the meeting edges of the cover and body and

the use of the corner pieces which connect 65 and secure the four strips forming the binder of the cover, the four braces or frame members which connect the four binder strips of the body and at the same time protect the entire length of the corners of the 70 body and finally the corner pieces of the body which also anchor the frame members or braces and thus the corner pieces of the cover and body and the frame members or braces make a strong metal construction 75 where most required in a cheap suit case of this character.

By this construction and arrangement the various reinforcing elements and portions 80 of the body and the cover are rigidly and permanently connected together to form a substantially continuous reinforcing frame, and the hinges, lock, and other trim and fittings of the case are secured in conjunction with these reinforcing portions. Further, 85 the arrangement of the parts is such that the cover and body strengthening frame portions reinforce one against the other when the case is closed in use.

While, in the foregoing, I have described 90 specific embodiments and have mentioned only certain possible modifications, it will be appreciated that in practice I do not limit myself to such specific details as herein set forth, but may resort to any practical modifications falling within the scope of the invention as defined in the appended claims.

I claim:

1. A suit case, consisting of a cover portion and a body portion, a binder for the inner edge of the cover portion consisting of 100 four strips fitting over the inner edges of the cover and having a short and long wall, a binder for the inner edge of the body portion consisting of four strips fitting over the inner edge of said body portion, and having a short and long wall, corner pieces connecting the meeting ends of the cover binder strips, fastenings for the strips and corner pieces passing through the corner pieces, 110 material of the cover and the long wall of the strips, corner pieces for connecting the meeting ends of the body binder strips, fastenings passing through the corner pieces, material of the body portion and long walls 115 of said strips, said corner pieces extending over the entire corners of said body portion and forming braces, corner pieces secured to said braces and body portion, hinges for the cover, fastenings anchored in the long walls 120 of the rear binder strips of the cover and body portion and a lock and spring catches anchored by fastenings to the longer wall of the front strips of the cover and body portions.

2. The suit case herein shown and described, consisting of the body and cover hinged thereto, the four binder strips for

the inner surrounding edge of the cover, the four corner pieces for the cover also secured to and connecting the ends of said binder strips, the four body binder strips, the four 5 angle shaped frame members fitting upon the corner edges of the body, secured to the body and to the ends of said body binder strips, and the four corner pieces secured to the corners of the body and to the angle 10 shaped frame members.

3. In a suit case, the combination with the cover and body of the case and the metal binders for the meeting edges of said cover

and body, of metal corner pieces fitting the corners of the cover fastenings securing the 15 corner pieces and metal binders, corner braces fitting the corners of the body, fastenings securing said corner braces and metal binders, corner pieces fitting the corners of said body, and fastenings passing 20 through the corner pieces and corner braces, thus providing separate corner pieces for the cover and body and intermediate braces for the corner of the body.

In testimony whereof I affix my signature.
SIMON GROSSMAN.
